(57) **CLAIM**

The ornamental design for a striker for latch, as shown and described.

DESCRIPTION

FIG. 1 is a front perspective view of a striker for latch showing our new design;

FIG. 2 is a rear perspective view thereof;

FIG. 3 is a front view thereof;

FIG. 4 is a top side view thereof;

FIG. 5 is a bottom view thereof;

FIG. 6 is a rear view thereof;

FIG. 7 is a left side view thereof; and,

FIG. 8 is a right side view thereof.

The broken lines showing details in the Figures are included for the purpose of showing environmental context of the design, and form no part of the claimed design.

1 Claim, 4 Drawing Sheets# US D672,631 S
